LOUNGE CHAIR

Joseph A. Handin, Alhambra, Calif.

Application April 12, 1956, Serial No. 41,048

Term of patent 14 years

(Cl. D15—11)

Fig. 1 is a perspective view of a lounge chair showing my new design;

Fig. 2 is a side elevation of one side thereof, the opposite side being identical, and,

Fig. 3 is a rear elevation of the lounge chair.

I claim:

The ornamental design for a lounge chair, substantially as shown.
